United States Patent Office.

ANDREW F. ATKINS, OF BRISTOL, CONNECTICUT.

Design No. 2,742, dated August 13, 1867.

DESIGN FOR A CLOCK-CASE.

The Schedule referred to in these Letters Patent and making part of the same.

TO ALL WHOM IT MAY CONCERN:

Be it known that I, ANDREW F. ATKINS, of Bristol, in the county of Hartford, State of Connecticut, have produced a new and improved Design for Clock-Case; and I do hereby declare that the following is a full, clear, and exact description thereof, which will enable others skilled in the art to make and use the same, reference being had to the accompanying photograph, making a part of this specification, in which—

a is the upper or dial-sash; *b* is the lower or tablet sash; *c c* are V-shaped pieces of mouldings placed between *a* and *b*, thereby ornamenting the places otherwise left vacant.

What I claim as my invention, and desire to secure by Letters Patent, is—

The V-shaped design placed as herein set forth and shown.
